UNITED STATES PATENT OFFICE

2,376,615

DRUM BEATING TOY

Eolina Nudelman, Chicago, Ill.

Application March 10, 1945, Serial No. 582,017

3 Claims. (Cl. 46—147)

My invention relates to rocking toys, and more particularly to the type designed for very young children, and one object of the invention is to provide a toy of this kind which procures additional action simulative of a military incident.

A further object of the invention is to employ an action development in the rocking toy which simulates the beating of a snare drum by a drum major.

Another object of the invention is to form the rocking toy with a mounting symbolical of a military post assumed by a drum major in action.

A still further object of the invention is to design the novel toy along lines of simplicity, compactness and rigidity.

With the above objects in view and any others which may suggest themselves from the description to follow, a better understanding of the invention may be had by reference to the accompanying drawing, in which—

Fig. 1 is a front elevation of the toy, showing the same at different positions in its movements;

Fig. 2 is a right-hand edge view of the toy; and

Fig. 3 is a fragmental section on the line 3—3 of Fig. 1.

Referring specifically to the drawing, the base 10 of the toy is a block of wood or other light material having a segmental form. Thus, with the rounded edge of the block at the bottom, the base may be rocked from one side to the other.

The base 10 is formed with a channel 11 in its top, and this channel is primarily employed for mounting an upright board 12. The board is set with its lower end against one wall of the channel and in the center of the base; and a spacer block 13 is added between the board and the other side of the channel. The assembly is then secured by nails, glue or other suitable means, so that the board 12 becomes rigidly attached to the base.

The board 12 is formed with a gabled top 14 to simulate a sentry house; and the front of the board carries the picture 15 of a drum major.

The drum major picture is developed in two respects. In the region of the chest is a block 16 simulating arms of the figure in grouped relation, the upper portion of the block being pivoted in the center on a nail 16a which is driven into the board 12. The block also carries a pair of sticks 17 appearing to be carried by the arms of the figure in respect to a snare drum.

A second development of the board 12 is a

semi-cylindrical mounting 18 below the drum sticks 17 and set at an oblique angle to simulate the snare drum referred to in the position it is usually carried by a drummer boy or drum major.

The relation between the block 15 and the drum mounting 18 is such that the drum sticks 17 rest on the top of the drum mounting when the toy is positioned with the figure upright—as shown by full lines in Fig. 1—or rocked toward the left. However, when the figure is rocked toward the right—such as to the position indicated by dotted lines in the same illustration—the block 16 swings to carry the drum sticks 17 away from the drum mounting 18. Thus, the rocking of the toy to and fro results in an action similar to the beating of a snare drum as the drum sticks are raised and lowered by the arms of the drummer.

20 The toy carries an additional development which is a common attraction to children growing out of the infant stage. This attraction is in the form of a pair of beads 19 which are slideable on horizontal rods 20. These occur short distances above the base of the toy and extend outwardly from the board 12 to a pair of posts 21, the latter being secured by nails 22 or other suitable means in the channel 11. Thus, when the toy rocks to and fro the beads 19 will slide 25 accordingly and add to the alluring effect or action.

It will be evident from the above description that I have provided a toy which employs a basic rocking movement for the purpose of inducing an action symbolical of an attractive military incident or practice. Thus, the action of the blocks 16 simulates that of the drummer's arms as they swing up and down to apply the drum sticks or raise them from the drum. Thus, 30 the block and drum stick assembly is the only part which has a relative motion in respect to the balance of the toy, which is virtually one solid piece. The invention is thus simple in its action and construction.

45 While I have described the invention along specific lines, various minor changes or refinements may be made therein without departing from its principle, and I desire to consider such changes and refinements as coming within the 50 scope and spirit of the appended claims.

I claim:

1. A toy comprising a base with a curved bottom to be rockable from side to side, a column rising from the base, a frontal abutment carried 55 by the column, and a member pivotally suspended

from the column above said abutment, the lower portion of the member meeting the abutment when the base is rocked toward one side, and swinging away from the abutment when the base is rocked toward the opposite side.

2. The structure of claim 1, that face of the abutment which is met by said portion being inclined.

3. The structure of claim 1, said column being a flat board, and that face of the abutment which is met by said portion being at right angles to the board and inclined.
